United States Patent Office

Des. 190,878
Patented July 11, 1961

190,878

PITCHER

Ronald A. Bradford, Chicago, and Ralph La Zar, Evans-ton, Ill., assignors to Arthur Salm Inc., Chicago, Ill., a corporation of Illinois

Filed May 6, 1959, Ser. No. 55,801

Term of patent 14 years

(Cl. D44—21)

Fig. 1.

Fig. 2.

Fig. 3.

Fig. 4.

FIG. 1 is a perspective view of a pitcher showing our new design;

FIG. 2 is a top plan view thereof;

FIG. 3 is a front elevational view thereof; and

FIG. 4 is a sectional view thereof, taken on the line 4—4 of FIG. 2.

We claim:

The ornamental design for a pitcher, substantially as shown.
